UNITED STATES PATENT OFFICE.

DAVID APSTEIN, OF BRIDGEPORT, CONNECTICUT.

TIRE-PLUG.

No. 825,287.

Specification of Letters Patent.

Patented July 10, 1906.

Application filed October 24, 1905. Serial No. 284,160.

To all whom it may concern:

Be it known that I, DAVID APSTEIN, a citizen of the United States, and a resident of Bridgeport, in the county of Fairfield and State of Connecticut, have invented certain new and useful Improvements in Tire-Plugs, of which the following is a specification.

This invention relates to new and useful improvements in pneumatic-tire plugs, such as are employed for closing punctures and the like, and is adapted to be made from metal with a suitable protective covering of soft air-proof material.

It is the object of my invention to produce a metal plug for closing holes in pneumatic tires which shall be exceptionally simple and inexpensive to manufacture and which may be accordingly sold and used as cheaply as other forms of plugs now upon the market, to provide a plug which will not injure or wear the tire and which shall be especially adapted to conform to the shape of a tire when applied.

With the above objects in view my invention resides and consists in the novel construction and combination of parts shown upon the accompanying sheet of drawings, forming a part of this specification, upon which similar characters of reference denote like or corresponding parts throughout the several figures, and of which—

Figure 1 shows a perspective view of my improved plug complete; Fig. 2, a side view of the same; Fig. 3, a vertical cross-section taken on line 3-3 of Fig. 2. Fig. 4 is a detail cross-section through a tire-tread, showing my plug applied thereto. Fig. 5 is a plan view of the blank from which the head of the plug is formed. Fig. 6 is an inverted plan view of a modified form of head, showing the edge of the stock turned in. Fig. 7 shows a longitudinal sectional and plan view of a further form of head embodying my invention and showing ribs on two sides of the pocket. Fig. 8 is a cross-section similar to Fig. 3, but illustrating a modification. Fig. 9 shows a cross-section and plan view of a plug, the rubber covering upon the head being distended.

As previously stated, it is the prime object of my present invention to produce a plug which can be manufactured and sold at a very low price, and with that in view I have devised my present plug, which is formed substantially of three parts of metal and a rubber covering for the head and nut. This

head in my present device is formed from a single piece of metal—such, for instance, as brass—being first blanked out and then stamped up to the required shape to form the novel construction embodied in the head.

Referring in detail to the characters of reference marked upon the drawings, A indicates the head of the plug as a whole, to which is swivelly connected a screw-threaded shank B, adapted to receive a rubber nut C. The head, generally speaking, is of an oval shape, having pointed ends d d, adapted for insertion into a puncture of a tire after the style of plugs of this character. After the plug is inserted the head is adjusted against the inside of the tire and the nut upon the shank is set up against the face of the tread, after which the threaded shank is cut off close to the face of the nut.

The head of my present plug is formed of a single piece of sheet metal in a very simple manner. It is first blanked out flat, as shown in Fig. 5, which shows a blank of a general oval outline having ears e e on either side of its middle portion. The central part of the blank is cupped up to form a pocket f for the head k of the shank, while the ears before mentioned are deflected in and down to cover the sides of the enlargement or shank and to hold the same in the pocket in a way to allow the said shank to be either rotated or swung forward or backward to either position indicated in dotted lines of Fig. 2, which position is that which said shank would assume when being shoved into a tire.

The outer edges of the head may be left plain, as indicated in Figs. 1, 2, and 7, or they may be turned in slightly to form a reinforced edge g, as shown in the modified construction, Fig. 6. The central part of the head may be also provided with a stamped rib h, as shown in Fig. 7, leading into the pocket f from each side to better permit the shank to be swung in two directions and to strengthen the head, if desired. A suitable flexible covering i may be used to cover the head and can be applied by molding around the head, as shown in Figs. 1 and 3, to protect the tire from the edges of the head, or the said parts may be covered by a dipping process or otherwise.

In Fig. 8 I have shown a round cup j to form the socket for the ball of the shank, and have shown the rubber covering i deflected in to hold said cup, thus forming a pocket which will not bind the head of the shank,

while in Fig. 9 the cup is omitted, the head being seated in metal pocket and covered with a rubber covering the edges *l* of which are extended, as shown.

5. Having thus described my invention, what I claim, and desire to secure by Letters Patent, is—

1. A pneumatic-tire plug, comprising a head formed of a single piece of sheet metal having a central pocket therein, and an integral ear on either side turned in over said pocket, to partially inclose the same, a threaded shank with a round head mounted in said pocket, and a nut upon the shank.

15 2. A pneumatic-tire plug, comprising a head formed of a single piece of sheet metal having a central pocket therein, an ear on either side turned in over said pocket to partially inclose the same, a threaded shank 20 with a round head mounted in said pocket, and a flexible covering for the face of the head.

25 3. A pneumatic-tire plug, comprising a head formed of a single piece of sheet metal blanked out to form pointed ends, a pocket central of the head, integral ears turned in from opposite sides to inclose the top side edges of the pocket, a threaded shank mounted intermediate of said ears having an enlarged head fitted within the socket, and a nut upon said shank.

35 4. A pneumatic-tire plug, comprising a head formed of a single piece of sheet metal comprising pointed ends, and oppositely-located ears turned from the edge of the sheet to form a pocket thereunder, a shank mounted intermediate of the inturned ends of said ears having an enlargement rotatably mounted within the pocket, and a nut upon the 40 threaded shank.

45 5. A pneumatic-tire plug, comprising a head formed of sheet metal, having a pocket and longitudinal ribs extending on two sides therefrom, ears turned in from the opposite

edges of the sheet over the pocket to partially inclose the same, a shank mounted intermediate of said ears bearing an enlargement to rotate within said pocket, and a nut upon the said shank.

50 6. A pneumatic-tire plug, comprising a head formed of a single piece of sheet metal having a central pocket therein, oppositely-located ears turned in over the pocket from the two side edges of the head, and a rib along the remainder of the edge of the head formed by the turning in of said edge, a threaded shank intermediate of the ears having an enlargement to engage the pocket and nut upon the shank.

60 7. A pneumatic-tire plug, comprising a head formed of a single piece of sheet metal having a central pocket therein, a threaded shank with a round head seated in the pocket, and a rubber covering for the head deflected in to operatively inclose the head in 65 the pocket.

70 8. A pneumatic-tire plug, comprising a head formed of sheet metal and having a central pocket therein, a threaded shank with a round head seated in the pocket, and a rubber covering for the head and having a flange deflected in to operatively inclose the head in the pocket.

75 9. A pneumatic-tire plug, comprising a head formed of a single piece of sheet metal having a central pocket therein, integral ears on either side turned in over said pocket to partially inclose the same, a threaded shank having an enlarged head with an oval end and flattened under side to form shoulders, 80 and a nut upon the shank.

Signed at Bridgeport, in the county of Fairfield and State of Connecticut, this 21st day of October, A. D. 1905.

DAVID APSTEIN.
